(57) **CLAIM**

The ornamental design for a non-stick drinking glass, as shown and described.

DESCRIPTION

FIG. 1 is a perspective view from below of a non-stick drinking glass of the present design;

FIG. 2 is a front elevational view of FIG. 1, the rear and side elevational views not being shown as these views are identical to the front elevational view;

FIG. 3 is a top plan view of FIG. 2;

FIG. 4 is a bottom plan view of FIG. 2;

FIG. 5 is a front elevational view of a second embodiment of the present design, similar to FIG. 1 but is of a non-stick drinking glass having different proportions, the rear and side elevational views not being shown as these views are identical to the front elevational view;

FIG. 6 is a top plan view of FIG. 5;

FIG. 7 is a bottom plan view of FIG. 5;

FIG. 8 is a front elevational view of a third embodiment of the present design, similar to FIG. 1 but is of a non-stick drinking glass having tapered rather than straight sides, the rear and side elevational views not being shown as these views are identical to the front elevational view;

FIG. 9 is a top plan view of FIG. 8;

FIG. 10 is a bottom plan view of FIG. 8;

FIG. 11 is a front elevational view of a fourth embodiment of the present design, similar to FIG. 8 but is of a non-stick drinking glass having a different styling, the rear and side elevational views not being shown as these views are identical to the front elevational view;

FIG. 12 is a top plan view of FIG. 11; and,

FIG. 13 is a bottom plan view of FIG. 11.
